(57) **CLAIM**

The ornamental design for a jig and spoon, as shown and described.

DESCRIPTION

FIG. 1 is a front elevation view of my jig and spoon

FIG. 2 is a top plan view thereof; and,

FIG. 3 is a right side view, the left side being a mirror image thereof; and,

FIG. 4 is a perspective view of the jig and spoon.

My jig and spoon is a original design characterized by the use of environmentally friendly components.
